HUMIDIFIER

Soren K. B. Larsen, Minneapolis, Minn.

Application September 16, 1937, Serial No. 164,185

8 Claims. (Cl. 261—92)

This invention relates to a humidifying device and particularly to such a device comprising a portable unit which can be disposed in the rooms to be humidified.

5 It is an object of this invention to provide a humidifier enclosed in a casing and comprising readily accessible and removable parts as well as one which can be very easily operated and controlled. It is a further object of the invention to provide a self contained humidifier having a supply of water therein and simple and efficient means for lifting and distributing said water so that it may be easily evaporated.

10 It is still another object of the invention to provide a humidifier lifting and distributing means of simple, novel and efficient construction.

15 These and other objects and advantages of the invention will be fully set forth in the following description made in connection with the accompanying drawings in which like reference characters refer to similar parts throughout the several views and in which:

Fig. 1 is a view in side elevation of the casing containing the device;

20 Fig. 2 is a central vertical longitudinal section through the device;

Fig. 3 is a plan view of the device with the casing cover removed;

25 Fig. 4 is a vertical section taken substantially on line 4—4 of Fig. 2 as indicated by the arrow;

Fig. 5 is a vertical section taken substantially on line 5—5 of Fig. 2 as indicated by the arrow;

30 Fig. 6 is a partial view in vertical section taken substantially on line 6—6 of Fig. 2 as indicated by the arrows; and

35 Fig. 7 is an end view of one of the bearings used showing the supported shaft therein.

40 Referring to the drawings, a humidifier is shown comprising a casing 10. While this casing might take various forms, in the embodiment of the invention illustrated, it is shown as rectangular in horizontal and vertical cross section. Said casing comprises a comparatively wide bottom strip 10a which extends around four sides thereof. Said strip is reversely folded at its bottom and is further reversely folded at its top edge and provided with a groove open at its top in which is received the lower edges of the reticulate side panels 10b and the reticulate end panels 10c. Said casing has a top strip 10d somewhat narrower than the strip 10a also extending about four sides of the casing, the same having its top edge bent at right angles and again reversely bent to form a top flange 10e. The bottom of strip 10d is also reversely bent and pro-

vided with a groove opening downwardly in which is received the upper edges of the reticulate panels 10b and 10c. Between the strips 10a and 10d are disposed at the corners of the casing angle posts 10f having sides at right angles, the outer surfaces of which are substantially flush with the outer surfaces of strips 10a and 10d. All of said members 10a, 10d and 10f are preferably made of sheet metal and the corner posts 10f are secured at their top and bottoms to strips 10a and 10d in any suitable manner as by welding. Corner posts 10f have their edges at right angles and provided with vertically extending grooves which receive the end edges of the panels 10b and 10c. Posts 10f are also provided at their bottoms with horizontal flanges 10ff which are perforated to have pass therethrough the headed screws 11 for a purpose to be later described. A cover 12 having a vertically depending flange 12a extending thereabout is provided for casing 10, 20 said cover being shown as imperforate. A pan or receptacle 13 is provided which is also of rectangular form in horizontal and vertical cross section and is of a size to pass easily within the strip 10a. Pan 13 has inwardly extending lugs 25 13a at its corners and adjacent its top which are tapped to receive the screws 11, which screws support said pan and hold it in place. The bottom of pan 13 is substantially flush with the lower edges of strips 10a. A bearing member 14 30 has a flange 14a secured to the bottom of pan 13 by any suitable means such as rivets, said bearing having a standard 14b in the form of a rod threaded at its upper end on which is adjustably mounted the threaded bearing portion 35 14c having a vertically extending open-ended slot therein. Another bearing 15 having similar parts is secured some distance from bearing 14, the same having the threaded and adjustable upper bearing portion 15c. Portion 15c also has a vertically extending slot therein open at its upper end. A shaft 16 has one end supported in the slot in bearing portion 14c and has its other end received in the slot in bearing portion 15c. Shaft 16 has secured thereto adjacent its ends frames 40 17, each having a hub secured to said shaft with radially and circumferentially spaced lugs thereon from which extend radially the rods 18 having their ends secured in said lugs. Rods 18 at their outer ends have secured thereto and extending therebetween metal strips 19. A plurality of spirally wound sheet screen members 20 are secured to the strips 19 at one end and to rods 18 at their other ends, said screens being arranged in nested and overlapping relation, as 45 50 55

shown in Fig. 4. One screen 20 has one end or longitudinal edge thereof secured to the strip 19 shown at the right hand end of the horizontal rod 18 at the right hand side of Fig. 4, said screen 5 extending in helical relation for one and one-quarter revolutions and has its ends secured to the vertically extending rods 18. Another one of the screens 20 has its ends or longitudinal edge secured to the strip 19 at the bottom of Fig. 4 10 and the same extends for one and one-quarter revolutions in helical form and has its end secured to the horizontally extending rods 18 at the right of Fig. 4. Similarly the other two screen members 20 have one end or longitudinal edge secured to the strip 19 at the top and the 15 left hand side respectively of Fig. 4 and the same extends through one and one-quarter revolutions and have their other ends secured to the rods 18. The convolutions of screens 20 are thus arranged 20 in radially and equally spaced relation and said screens form a member of general cylindrical form. The strips or bars 19 are slightly offset at one end and have secured thereto as by spot welding a cylindrical rim 21. Rim 21 rests at 25 its upper and its inner or concave side upon a roller 22. Roller 22 is secured to one end of a small shaft 23 journaled in a bearing 24 held in the bight of a bracket member 25 formed of a strip or bar of rectangular cross section which 30 has sides diverging downwardly and provided with outwardly extending horizontal foot portions which are secured to the bottom of pan 13 by the headed screws 26. The upper or bight portion of bracket 25 has vertically extending 35 spaced portions immediately below the bearing 24 through which passes the headed and nutted bolt 27 holding the side portions of bracket 25 in position and clamping bearing 24 therein. Shaft 23 has secured thereto between roller 22 40 and bearing 24 a grooved wheel 28 having in its periphery a frictional tire or annular member 29 of rubber or similar friction material. A motor 30 is disposed in casing 10 and has trunnion pins 31 extending horizontally from the sides thereof 45 and journaled in the vertically extending brackets 32 which have horizontal flanges or foot portions engaging the bottom of pan 13 and secured thereto by the screws 33. Washers or bushings 34 of insulating material are disposed about pins 31 at either side of brackets 32. Motor 30 is thus 50 mounted for swinging movement about pins 31 and said motor has secured to the armature thereof and projecting therefrom a shaft 35 which in the normal position of motor 30 engages the bottom of tire 29. A fan 36 is secured to 55 shaft 35 adjacent motor 30. Motor 30 has secured thereto and projecting upwardly therefrom, a rod 37. A bracket 38 has a vertical flange secured to one end portion of strip 10d and has 60 a horizontally extending portion which is reversely bent at one end and extends about the upper end of rod 37. Said bracket thus having a U-shaped or hook-shaped end. A screw 39 extends between the sides of bracket 38 and a 65 cam lever 40 is journaled on screw 39, said lever having a handle or finder portion 40a. It will be seen from Fig. 2 that screw 39 is eccentric to lever 40 and that if said lever is swung upwardly about said screw it will cam or push rod 37 to 70 the left as seen in Fig. 2, thus oscillating motor 30 and depressing shaft 35. Conductors 30a are shown as leading from motor 30 and the same extend through an insulating bushing 41 in the end panel 10c.

75 It is desirable to maintain water at a certain

level in pan 13 and for this purpose a valve 42 is secured to one of the brackets 32, the same having an inlet pipe to tube 42a extending through said bracket to which may be connected a flexible tube 43 which may extend to a suitable water supply. Valve 42 may be opened or closed by the movement of a vertically extending plunger rod 42b which is pivoted at its upper end to one end of a lever 44 having a float 45 at one end thereof. Lever 44 is pivoted adjacent its other end to a downwardly extending bracket 46 having a reduced threaded portion extending through an angle bracket 47 which is secured in any suitable manner to bracket 32, said reduced portion of bracket 46 being equipped with a nut 48 at the upper side of bracket 47.

In operation, the device will be disposed in a suitable location in the room to be humidified and it may be conveniently supported upon a radiator. Tube 43 will be connected to a source of water supply such as to the pipes of a city supply and valve 42b will be adjusted so that float 45 will maintain a certain level in pan 13. It will be noted that the lower part of the screen member formed by the screens 20 extends into the pan 13 and will thus extend into the water therein. Current will be supplied to motor 30 and said motor will be operated. Shaft 35 will be rapidly rotated and this will rotate fan 36 so that a current of air will be directed through the screens 20 and out through the reticulate panels of casing 10. Shaft 35 engages the bottom of member 29 on wheel 28 and said wheel is rotated by the friction of said shaft. Wheel 28 rotates roller 22 and since rim 21 carrying the screen member rests on roller 22, said rim and screen member are slowly rotated by said roller. The screen members 20 pick up moisture from pan 13 and carry it upwardly as they rotate. This moisture is evaporated by the current 40 of air from fan 36 and passes out into the atmosphere which is thus humidified. The level of water as stated, is maintained in pan 12 by the float mechanism. It will be noted that shaft 16 normally rests in bearing portion 44c but does not normally engage the bottom of the groove in bearing portion 15c. The device can be operated of course, without the continuous water supply and in such case water would have to be periodically placed in pan 13. This can be done by removing the cover 12. When water is thus poured into pan 13 it is desirable to have the screen portion of the screens 20 uppermost instead of bars or strips 19. In order to easily turn the screen member to the desired position cam lever 40 can be swung upwardly to push rod 37 to the left as shown in Fig. 2 and thus swing motor 30 and move shaft 35 downwardly. This disengages shaft 35 and member 29 on wheel 28 and the screen can then be turned to the desired position. Water can then easily be poured through the screen into the pan 13. When lever 40 is swung downwardly, motor 30 will resume its normal position and shaft 35 will reengage member 29 so that wheel 28 will be driven. To guard against the operator forgetting to move lever 40 downwardly, said lever is positioned so that when cover 12 is placed on the casing it will engage lever 40 and move the same downwardly thus reengaging shaft 35 and member 29.

70 It will be noted that the pan 13 carries the screen member, motor and associated parts and that these and the pan are supported by the screws 11. By removing screws 11 therefore, the pan 13 with the parts carried thereby can easily 75

- be removed from the casing or the casing can be lifted from about the pan and other parts. The bearing portions 14c and 15c can be brought to the desired position by merely being rotated on their standards.
- 5 The screen members 20 have binding at their longitudinal edges, the binding at one end being secured to members 19 and at the other end being secured to the rods 18 as shown in Fig. 6.
- 10 By having the screen members of spiral form they will be moistened by passing through the water in pan 13 even though there is very little water in the pan. The end of the screen at its largest diameter will pass through the water and the water will then run down the screen as it rotates so that it will reach the innermost convolution. This would not be the cause if the screens were of cylindrical form and of different diameters in concentric relation.
- 15 20 It is obvious that the device could be made of such size that it could be placed in the basement of a dwelling and air taken therefrom conducted by a suitable conduit to the rooms to be humidified. The humidified air could also if desired, be directed into the delivery conduit of a hot air furnace so that it would thus be delivered to the rooms to be humidified.
- 25 From the above description it is seen that applicant has provided a very simple and highly efficient humidifying device which may be automatically operated. The device has ample capacity for giving the desired humidification. The device can be made of very pleasing appearance by suitably finishing the outside of the casing.
- 30 35 While various forms of perforations could be used for the reticulate panels 10b and 10c in the embodiment shown, the perforations are arranged to represent the well known cane or rattan weaving commonly used on chairs. A very attractive device is thus formed. The device has been amply demonstrated in actual practice and found to be very successful and efficient and the same is being commercially made.
- 40 It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.
- 45 What is claimed is:
1. A humidifier having in combination, a casing, a pan in said casing adapted to contain water, a bearing upstanding from one end of said pan, a screen member of general cylindrical form having a central shaft supported in said bearing, said member extending into said pan, a second bearing having a vertically extending slot 50 therein for receiving the other end of said shaft, said screen having a cylindrical rim at the end adjacent said second bearing, a friction roller on which said rim rests on its upper concave side, means for rotating said roller to rotate said screen and means for directing a current of air through said screen.
